UNITED STATES PATENT OFFICE.

FAY C. HAYES, OF ALTAMONT, NEW YORK.

FILE.

No. 892,957.

Specification of Letters Patent.

Patented July 7, 1908.

Application filed November 6, 1907. Serial No. 401,041.

To all whom it may concern:

Be it known that I, FAY C. HAYES, of the village of Altamont, Albany county, New York, have invented certain new and useful 5 improvements in files and manner and style of keeping account of sales, debit and credit, and other business memoranda of merchants, millers, contractors, and other business transactions, of which the following is a specification.

10 The object of my invention is to provide a new and improved file for bills, accounts and such like papers used by merchants and dealers and others handling various sorts of 15 goods, one object to be gained to cut short much bookkeeping and rewriting of bills and much clerical work and in keeping the bills where at a mere glance the total amount due 20 can be ascertained without removing the whole bill from the file at a loss of more or less time.

In the drawing Figure 1 shows a front end view of my invention with the drawers removed showing the interior construction in part, 25 Fig. 2 a plan view of one of the drawers, Fig. 3 a face view of the bill carrier, Fig. 4 an edge view of the bill carrier showing its construction, Fig. 5 a plan view of one of the bill carriers enlarged to show the manner in 30 which the bill is carried and the portion thereof visible when in the file and Fig. 6 a form of a bill adapted to the file showing the bill of a supposititious customer, Smith, A. J. showing his whole bill made up of one day's 35 trading with the amount forward added to it leaving a total of \$13.00 visible at the down- 40 ward right hand corner of that much of the exposed bill as is left visible by the construction of the file.

The numeral —a— shows the casing of the file, and —b— the stringers for the drawers at the front end of the casing. —c— represent spring wires affixed to said stringers or to some other convenient portion of the device and as they run backward to the rear of the casing they spring downward and rest upon the top surface of the bill carrier in its compartment in the drawer and prevents the leaves from opening and allowing the

bills to spill out even if the casing be turned 50 bottom side up.

—f— shows the partitions forming the spaces into which the drawer is divided.

—e— shows the openings in the rear of the drawer to accommodate the ends of the 35 wires —c—.

While but one drawer is shown the casing will accommodate 5 drawers.

—g— shows one of the bill carriers and the drawing shows it to be made of thin material like card board and in Fig. 4 it is seen to be put in shape by bending the card board over upon itself forming a loop and several of these loops are cemented together as shown at —h— in Fig. 4 their loose ends 65 overlapping each other and carrying a name plate —i— which is adapted to hold the name as a person or thing as may be desired, as seen in Fig. 5 where the name Smith, A. J. is seen so carried. The bill carriers —g— 70 lie in the compartments of the drawers as seen at Fig. 2 and can be taken from and replaced therein as may be desired. The drawers are indexed for convenience or have on them such letters of the alphabet as may 7 seem desirable. All the bills made out to Smith, A. J. would be kept in the one carrier, the top bill showing the total of all or such other information as might be desirable to be seen at a glance. The name holders 80 —i— are strips of metal folded over and riveted or otherwise fastened to the bill holders as seen at Fig. 4 and a small card is slipped into the name holder with the name written upon it.

Having now described my invention so that those skilled in the art to which it appertains may know how to make and use the same what I claim and desire to secure by Letters Patent is:

1. A file consisting of a casing having movable drawer like receptacles, and holders in said receptacles, said holders consisting of suitable material in strip like form folded over on itself, the top or exposed fold being movable and forming the cover of the holder, a plurality of said holders being attached together forming a succession of holders and

95

having means whereby the contents of each holder is at least partially visible substantially as described.

2. A file consisting of a casing having movable drawer like receptacles and holders in said receptacles and a resilient device entering said receptacle and pressing upon said holders said holders being slidable under the resilient device when the drawers are opened 10 and closed and arranged so that the resilient

device will, when the drawers are closed exert a closing pressure on the holders substantially as described.

In testimony whereof I have affixed my signature this 24th day of October, 1907, in 15 the presence of two witnesses.

FAY C. HAYES.
